BICYCLE PARKING STAND

Michael J. Lacivita, 3220 Eldora Drive,
Youngstown, Ohio

Filed Sept. 21, 1965, Ser. No. 87,097

Term of patent 14 years

(Cl. D90—18)

FIGURE 1 is a perspective view of a bicycle parking stand showing my new design from the front, one side and the top,

I claim:
The ornamental design for a bicycle parking stand, as shown.
